CLAIM

The ornamental design for a combined pipe coupler and plug, as shown and described.

DESCRIPTION

FIG. 1 is a top plan view of a combined pipe coupler and plug showing my new design;

FIG. 2 is a front elevational view thereof, the rear view being a mirror image thereof;

FIG. 3 is a bottom plan view thereof;

FIG. 4 is a right side elevational view thereof; and,

FIG. 5 is a left side elevational view thereof.
